UNITED STATES PATENT OFFICE.

FRANCIS L. PISCH, OF NEW YORK, N. Y.

DESIGN FOR A LANTERN-BODY.

SPECIFICATION forming part of Design No. 18,400, dated June 19, 1888.

Application filed May 7, 1888. Serial No. 273,138. Term of patent 7 years.

To all whom it may concern:

Be it known that I, FRANCIS L. PISCH, of the city, county, and State of New York, have invented a new and original Design for a Lantern-Body, of which the following is a specification, reference being had to the accompanying drawing, forming part thereof, in which the figure is a perspective of my newly-designed lantern body.

10 The leading feature of my design consists of a rectangular figure arranged centrally on each face of the lantern-body, narrow trapezoidal figures bordering the respective sides of the central figure, and jewel ornamentalations in the corner spaces outside the trapezoidal figures.

In the design, as shown in the drawing, each face A of the lantern-body is of rectangular shape, and centrally thereon is a diamond-shaped figure, B, the angles of which meet the

middle points of the respective border-lines of the face A. Along and parallel with each side of the figure B is a narrow trapezoidal-shaped figure, C, terminating at the respective border-lines of the face A, and in the corner spaces, D, outside the figures C, are ornamental jewels E. 25

I claim—

The design for a lantern-body herein shown and described, the same consisting of a rectangular figure, B, on each face of the lantern-body, narrow figures C outside the respective sides of the figure B, and jewel ornamentalations E in the corner spaces outside the figures C, as set forth.

FRANCIS L. PISCH.
